UNITED STATES PATENT OFFICE

WILLIAM LESLIE EDISON, OF WILMINGTON, DELAWARE, ASSIGNOR TO THE W. L. EDISON MANUFACTURING CORPORATION, OF WILMINGTON, DELAWARE, A CORPORATION OF DELAWARE

SIGNALING SYSTEM

Application filed September 11, 1928. Serial No. 305,272.

This invention relates to a high frequency alternating current system and more particularly to means for interconnecting the tubes of an amplifying system to prevent oscillation due to mutual interaction. The system herein disclosed is particularly adapted to the amplification of radio signals.

In order to prevent oscillation in the radio frequency amplification stages of radio sets 10 heretofore in common use various expedients have been adopted, among which may be particularly noted the use of neutralizing condensers, potentiometers for imparting a bias upon the grid, and so called "grid suppressors" which consist of resistances placed in the grid circuits. In the use of these devices, 15 the degree of amplification per stage is cut down to a considerable degree necessitating, for a satisfactory output, an excessive number of stages resulting in objectionable distortion.

It is accordingly the object of the present invention to provide an interconnecting means for the tubes of an amplifying system 25 and a circuit including this means which produces a high degree of amplification without oscillation, distortion, or the losses referred to. The interconnecting means specifically consist of a novel transformer, the 30 construction of which will be clear from the following description read in conjunction with the accompanying drawing, in which:

Fig. 1 is a diagrammatic illustration of a portion of a circuit embodying the improved 35 amplifying system;

Fig. 2 is a vertical section through the improved transformer; and

Fig. 3 is an elevation of the transformer 40 showing diagrammatically the connections thereof with the other elements of an amplifying system.

Referring first to Figs. 2 and 3, the transformer is designated at T and consists of a base 2 on which is mounted a cylindrical cup 4 of insulating material and having a top opening in which is threaded a cap 6 of insulating material. Suitably supported, as by a metallic bolt or rod extending through cap 6, is a metallic electrode 10, of copper for example, which is submerged in a suitable liq-

uid 12 contained in cup 4. The upper end of rod 8 is provided with a soldering lug 14 to which connection may be made.

Wound on the outside of the cup or cell 4 are primary and secondary coils P and S respectively. While these coils are shown as, and preferably are, mounted on cell 4, and in spaced relationship, they may be otherwise wound. It is, of course, obvious that the turns, shape of the cell, etc., will be determined by the circuit in which the transformer is used.

The liquid within the cell, similarly to that used in the cell described in my application for signaling system, Serial No. 288,563, filed June 27, 1928, may be of various types although water or an electrolyte solution is preferred. If it is desired to positively prevent spilling, the solution may be gelatinized as described in my prior application.

In Fig. 1 a number of radio frequency amplification stages are illustrated, corresponding elements of the various successive stages being designated by the same reference characters with different subscripts appended thereto. The primary P₁ of the first stage is shown as connected in an aerial circuit although it will be understood that current may be produced therein from any source as, for example, from a prior amplification stage. The secondary of the first transformer T₁, 75 tuned by a variable condenser C₁, is connected to the grid and cathode respectively of a tube V₁ containing the usual grid, plate and cathode elements, the latter of which is suitably heated.

The grid of tube V₁ is connected through a resistance R₁ with the electrode 10 of the first transformer cell. This resistance is preferably variable and of the order of 3000 to 4000 ohms. As will be explained hereafter, the resistance R must be of a proper value depending on the characteristics of the circuit for best operation and accordingly a variable resistance is convenient, although, for a carefully designed set, a fixed resistance of predetermined value may be used.

The plate of tube V₁ is connected through the primary P₂ of the second transformer T₂ and a suitable source of plate voltage B with

the cathode of tube V_1 . A broken connection is shown at α to indicate the inclusion of any desired number of amplification stages similar to the first, although only two amplification stages are illustrated. As a matter of fact it is found to be possible to use five stages of radio frequency prior to the detector.

The transformer connections prior to the second tube V_2 and detector V_3 are similar to those described in connection with the first tube and detailed explanation is believed unnecessary since the connections will be clear from Fig. 1, the parts being correspondingly designated. A grid leak L and condenser are included in the grid circuit of the detector V_2 .

While not shown, it will be clear that the plate output of the detector may be amplified at audio frequency in any desired or usual manner. Using the radio frequency amplification system shown, it is found to be particularly advantageous to amplify the output of the detector by the means described in my prior application referred to above.

With connections as described above, it is found that, when the sizes of cells and resistances R properly correspond, oscillation is effectively prevented thus permitting a high degree of amplification. It is important that the resistances R correspond to the other elements used since variation of a resistance from the proper limits, or disconnection thereof, throws the stage in which it is used into violent oscillation. It is preferable, for this reason, to employ variable resistances as described above.

It will be noted that there is no interposition of any resistance, potentiometer, or the like, in the grid circuit. Consequently there is no diminution of amplification which ordinarily results from the usual methods of suppressing oscillation. Also, by reason of the direct coupling of the grid with the incoming signals, there is no dependence of amplification on wave length and it is found that uniformity of amplification at all wave lengths is obtained. This uniformity is particularly noticeable in receiving short waves which are suppressed by the usual circuits.

Another effect is increased stability of the circuit since change of tubes does not necessitate readjustment of the circuit in order to prevent oscillation. Shielding of the radio frequency stages is also found to be unnecessary.

The action of the described circuit is not clearly understood and hence no explanation is given.

My copending application, Serial No. 414,919, filed December 18, 1929, contains broad claims generic to its disclosure and the disclosure of this application.

What I claim and desire to protect by Letters Patent is:

1. An amplifying system including a thermionic tube having cathode, grid and plate elements, a grid circuit joining the grid and cathode of the tube, means for impressing signals on the grid circuit, a cell including a body of liquid and an electrode contacting therewith, said electrode being connected with the grid. 70

2. An amplifying system including a thermionic tube having cathode, grid and plate elements, a grid circuit joining the grid and cathode of the tube, means for impressing signals on the grid circuit, a cell including a body of liquid and an electrode contacting therewith, said electrode being connected with the grid, and a coil in the grid circuit, said cell being in the field of the coil. 75 80

3. An amplifying system including a thermionic tube having cathode, grid and plate elements, a grid circuit joining the grid and cathode of the tube, a transformer comprising primary and secondary coils, the secondary coil being in the grid circuit, and a cell in the field of the transformer coils, said cell including a body of liquid and an electrode 85 90 contacting therewith, said electrode being connected with the grid. 95

4. An amplifying system including a thermionic tube having cathode, grid and plate elements, a grid circuit joining the grid and cathode of the tube, means for impressing signals on the grid circuit, and a cell including a body of liquid and an electrode contacting therewith, said electrode being connected with the grid through a resistance. 100

5. An amplifying system including a thermionic tube having cathode, grid and plate elements, a grid circuit joining the grid and cathode of the tube, means for impressing signals on the grid circuit, a cell including a body of liquid and an electrode contacting therewith, said electrode being connected with the grid through a resistance, and a coil in the grid circuit, said cell being in the field of the coil. 105 110

6. An amplifying system including a thermionic tube having cathode, grid and plate elements, a grid circuit joining the grid and cathode of the tube, a transformer comprising primary and secondary coils, the secondary coil being in the grid circuit, and a cell in the field of the transformer coils, said cell including a body of liquid and an electrode contacting therewith, said electrode being connected with the grid through a resistance. 115 120

7. An amplifying system including a plurality of thermionic tubes, each of which has cathode, grid and plate elements, a plate circuit joining the plate and cathode of one tube, a grid circuit joining the grid and cathode of a succeeding tube, and a transformer comprising primary and secondary coils included, respectively, in the said plate and grid circuits, and a cell in the field of the 125 130

transformer coils, said cell including a body of liquid and an electrode contacting therewith, said electrode being connected with the grid of said succeeding tube.

5 8. An amplifying system including a plurality of thermionic tubes, each of which has cathode, grid and plate elements, a plate circuit joining the plate and cathode of one tube, a grid circuit joining the grid and cathode of a succeeding tube, and a transformer comprising primary and secondary coils included, respectively, in the said plate and grid circuits, and a cell in the field of the transformer coils, said cell including a body of liquid and an electrode contacting therewith, said electrode being connected with the grid of said succeeding tube through a resistance.

9. A transformer comprising a cell, and 20 primary and secondary coils wound about the cell, said cell including a body of liquid, and an electrode contacting with the liquid.

10. A transformer comprising a cell, and 25 primary and secondary coils wound about the cell, said cell comprising a cup of insulating material, a body of liquid within the cup, and an electrode contacting with the liquid.

In testimony of which invention, I have hereunto set my hand at Wilmington, Del., 30 on this 8th day of September, 1928.
